ELECTRIC CLOCK

John G. Jolly, Cincinnati, Ohio, assignor to NuTone, Inc.,
Cincinnati, Ohio, a corporation of New York

Application February 26, 1958, Serial No. 49,800

Term of patent 14 years

(Cl. D42—7)

Figure 1 is a front perspective view of an electric clock showing my new design; and

Figure 2 is a top plan view thereof.

The bottom and two side profiles of the clock are identical to the profile shown in Figure 2 and the sides, back and bottom of the rectangular casing at the rear of the clock are substantially plain.

I claim:

The ornamental design for an electric clock, substantially as shown and described.
